UNITED STATES PATENT OFFICE.

EDWIN R. SMITH, WILLIAM R. RICE, AND JOHN R. JACKSON, OF FITCHBURG, MASSACHUSETTS, ASSIGNEES, BY MESNE ASSIGNMENTS, TO FEDERAL ADDRESSING MACHINE CORPORATION, OF BUFFALO, NEW YORK, A CORPORATION.

SHEET-FEEDING MECHANISM.

Original application filed November 4, 1922, Serial No. 599,122. Divided and this application filed September 29, 1924. Serial No. 740,442.

This application is a division of our prior application on addressing machine, Serial No. 599,122, filed Nov. 4, 1922 and relates particularly to the sheet feeding mechanism therein shown and described.

It is the object of our invention to provide mechanism for feeding envelopes, paper sheets or other similar articles to printing or addressing machines so designed that it will release the articles singly and successively to suitable conveying devices.

A particular feature of our invention relates to means for agitating the envelopes in the feed box or chute and for giving them initial advance movement toward delivery position.

Our invention further relates to arrangements and combinations of parts which will be hereinafter described and more particularly pointed out in the appended claims.

A preferred form of the invention is shown in the drawings in which

Fig. 1 is a sectional side elevation of our improved feeding mechanism; and
Fig. 2 is a sectional view, taken along the line 2--2 in Fig. 1.

Referring to the drawings, we have shown certain parts of an addressing machine including a table 20 and a continuously driven feed shaft 48 on which are mounted feeding rolls 49 (Fig. 2) which are each provided with pads 50 of rubber or other friction material extending over a portion only of the periphery thereof.

The rolls 49 are located adjacent the lower end of an inclined feed box or chute comprising a bottom 51, sides 52 and a curved top and end plate 53. The envelopes E placed in the feed box descend by gravity to the position indicated in Fig. 1, at which point the lowest envelope is advanced between the roll 49 and the curved end of the plate 51, where it is engaged by the friction pads 50. A series of retarding rolls 54 are mounted on a shaft 55 above and closely adjacent the rolls 49. The shaft 55 is positively driven from the shaft 48 by a chain and sprockets (not shown). The adjacent surfaces of the rolls 49 and 54 thus move oppositely and the upper rolls 54 act to brush back or retard any extra envelope advanced by the feed rolls 49.

In order to assist the advance movement of the lower envelopes toward the feed rolls, we have provided an agitating device comprising a pad or block 60 (Fig. 1) mounted on an arm 61 pivoted at 62 and intermittently engaged by a cam 63 (Fig. 2) on the feed shaft 48. The block 60 thus repeatedly engages the envelopes in the feed box, forcing them slightly backward and upward and then releasing them so that the lowermost envelope may be easily advanced by gravity to the feed rolls.

As each envelope is delivered singly by the rolls 49, it is received between conveyor belts 64 and 65. The upper belts 64 are supported on driving pulleys 66 fixed to a cross shaft 68 which is driven from the feed shaft 48. The lower belts 65 are mounted on driving pulleys 72, fast on a cross shaft 73. The shaft 73 is connected by gearing (not shown) to the upper conveyor shaft 68. By these connections, the upper and lower belts are continuously driven at the same speed.

By the construction shown, we provide a definite and accurate delivery of envelopes or other similar articles singly to an addressing or printing machine or for any other desired purpose. The provision of the agitating device is found to greatly improve the operation of the machine and to reduce the chances of a double delivery.

Having thus described our invention and the advantages thereof, we do not wish to be limited to the details herein disclosed otherwise than as set forth in the claims, but what we claim is:—

1. In an envelope addressing machine, an inclined feed box having a bottom partially open at its lower edge, a feed roll rotatable adjacent said open portion and intermittently presenting a friction surface effective to withdraw an envelope from said box, a retarding roll mounted above said feed roll, means to rotate said rolls so that the adjacent faces thereof move in opposite directions, and means to agitate the envelopes in said box to facilitate downward feeding thereof.
2. In an envelope addressing machine, an inclined feed box having a bottom partially open at its lower edge, a feed roll rotatable adjacent said open portion and intermitt-

tently presenting a friction surface effective to withdraw an envelope from said box, a retarding roll mounted above said feed roll, means to rotate said rolls so that the adjacent faces thereof move in opposite directions, a member extending through the lower end of the box and means to alternately raise and release said member to agitate the envelopes in said box.

10 3. In an envelope addressing machine, an inclined feed box having its lower end partially open, a driven shaft, a feed roll mounted on said shaft rotatable adjacent

said open portion and intermittently presenting a friction surface effected to withdraw an envelope from said box, yielding member extending into the lower end of said box and means mounted on the feed roll shaft to alternately raise and release said member to agitate the envelopes in said box. 15 20

In testimony whereof we have hereunto affixed our signatures.

EDWIN R. SMITH.
WILLIAM R. RICE.
JOHN R. JACKSON.
